[57] CLAIM

The ornamental design for a convertible golf club, as shown
and described.

DESCRIPTION

FIG. 1 is a perspective view of a convertible golf club
showing my new design;

FIG. 2 is a perspective view of a second embodiment of a
convertible golf club as disclosed in FIG. 1;

FIG. 3 is an enlarged fragmented portion of the lower section
of FIG. 1;

FIG. 4 is a right side elevational view of FIG. 3;

FIG. 5 is a left side elevational view of FIG. 3;

FIG. 6 is a top plan view of FIG. 3; and,

FIG. 7 is a bottom plan view of FIG. 3.

The sides not disclosed on the handle portion of the drawing
is identical to that shown.

The broken line showing a human figure in FIGS. 1 and 2
is for illustrative purposes only and forms no part of the
claimed design.
